United States Patent Office

Des. 206,429
Patented Dec. 13, 1966

206,429

CAKE OR THE LIKE

David B. Eckelman, Shawnee Mission, Kans., assignor to Interstate Bakeries Corporation, Kansas City, Mo., a corporation of Delaware

Filed Dec. 4, 1963, Ser. No. 77,659

Term of patent 14 years

(Cl. D8—1)

FIG. 1 is a perspective view of a cake or the like embodying my new design;

FIG. 2 is a top view;

FIG. 3 is an end view;

FIG. 4 is a side view;

FIG. 5 is a cross-sectional view taken at the line 5-5 of FIG. 4, and

FIGS. 6-10 are views corresponding with those of FIGS. 1-5 but illustrating a modified form of the cake or the like shown in FIG. 1.

I claim:

The ornamental design for a cake or the like, substantially as shown and described.
